UNITED STATES PATENT OFFICE.

RONALD F. McFEELY, DECEASED, LATE OF BEVERLY, MASSACHUSETTS, BY E. MARK SULLIVAN, ADMINISTRATOR, OF BOSTON, MASSACHUSETTS, ASSIGNOR TO UNITED SHOE MACHINERY CORPORATION, OF PATERSON, NEW JERSEY, A CORPORATION OF NEW JERSEY.

MACHINE FOR LASTING BOOTS AND SHOES.

1,356,540.

Specification of Letters Patent.

Patented Oct. 26, 1920.

Application filed January 28, 1918. Serial No. 214,163.

To all whom it may concern:

Be it known that RONALD F. McFEELY, deceased, late of Beverly, in the county of Essex and State of Massachusetts, invented 5 certain Improvements in Machines for Lasting Boots and Shoes, of which the following description, in connection with the accompanying drawings, is a specification, like reference characters on the drawings indicating 10 like parts in the several figures.

This invention relates to machines for use in the manufacture of boots and shoes and is herein shown as embodied in a lasting machine of the type in which successive portions of a shoe upper are worked into lasted position. For convenience in illustrating the invention, it is herein shown as embodied in a machine especially adapted to operate upon shoes of the type in which the shoe 15 upper is worked into lasted position on the shoe bottom and secured by the use of cement applied in any suitable manner such as practised, for example, in the manufacture of vulcanized rubber sole shoes.

20 An important feature of the invention is to be recognized in novel means for working an upper toward lasted position by means of frictional engagement with the upper. As herein shown, this means is arranged for operation upon the upper in such manner as to produce a frictional drag upon the upper, and to this end additional means are provided to maintain the margin of the upper in engagement with the frictional means. 25 The application of a frictional drag to the margin of the shoe upper, in addition to drafting the upper toward lasted position over the shoe bottom, also tensions the upper about the last so that it conforms to the 30 contour of the last and eliminates any fullness of the upper material on the last.

The means for frictionally engaging the shoe upper comprises, in the preferred construction shown, a rotating member having 45 a continuous rubbing surface adapted to act upon the margin of the upper, and the means coöperating with the said member for maintaining the upper in position to receive the action of the rubbing surface consists of a 50 finger located adjacent to the rubbing surface and between which and the rubbing surface the upper is disposed. Preferably also,

as shown and in accordance with a feature of the invention, the rubbing surface which produces the frictional drag upon the margin of the upper is inclined obliquely, transversely and longitudinally, to the plane of the shoe bottom so that the shoe upper, when subjected to such action, is, in effect, plaited whereby the surplus material occasioned in 60 conforming the upper to the contour of the last may be disposed on the shoe bottom to the best advantage.

An important feature also is to be recognized in a novel combination of means for applying a frictional drag upon the margin of the shoe upper to dispose the margin toward lasted position over the shoe bottom and tension the upper about the last, with co-operating means arranged to lay the margin 70 of the shoe upper into lasted position on the shoe bottom before the tension of the upper is relaxed. As preferably constructed, the upper positioning and tensioning means permits the shoe to be moved into position to be 75 operated upon in such manner that the laying means operate in continuation of the said positioning and drafting means, whereby the upper is subjected to the action of the two means at all times, thus insuring a 80 positive and accurate treatment of the upper as it is worked over on to the shoe bottom.

In the illustrated embodiment of the invention, the means for laying the margin of the positioned upper into lasted position on 85 the shoe bottom also comprises a continuous acting surface located laterally adjacent to the inclined rubbing surface of the machine and so arranged with respect to the lateral surface that it applies a laying action to the 90 margin of the shoe inwardly and downwardly against the shoe bottom. The laying action of this surface is preferably directed at substantially right angles to the edge of the last, and, since the action of the rubbing 95 surface is directed angularly across the margin of the shoe upper, the shoe upper is maintained taut for the action of the laying surface.

The above and other features of the invention, including certain details of construction and combinations of parts, will now be described with reference to the accompanying drawings and pointed out in the claims.

The novel improvements in methods of making shoes herein disclosed constitute the subject-matter of a co-pending application Serial No. 214,162 filed Jan. 28, 1918.

5 Figure 1 is a perspective view of a machine embodying the invention; and

Fig. 2 is a plan view illustrating the manner of operation of the machine herein illustrated.

10 The frame 2 of the machine supports a driving shaft 4 carrying a driving pulley 6 which is belted to a suitable source of power for rotating the driving shaft 4. Secured on the end of the shaft 4 by means of a 15 washer and nut 8 is a wheel 10, the size of the outer portion of which is such as to enable a considerable area of upper material to be acted upon at one time. The periphery of the wheel 10 preferably presents a continuous 20 acting surface 12 disposed in a plane substantially parallel to the axis of rotation of the wheel 10. Formed in continuation of the laying surface 12 on the wheel 10 or laterally adjacent thereto is a 25 rubbing surface 14 having alternate ribs and grooves 16 formed thereon. This surface 14 is located adjacent to the laying surface 12 opposite to the direction of feed of the shoe, and it is so formed on the wheel as to be disposed 30 in a plane at substantially 45 degrees to the laying surface 12 or the axis of rotation of the wheel 10.

The frame 2 of the machine has guideways 17 in which is mounted a sliding block 18 the lower end of which is provided with a depending ear 20 carrying a transversely projecting shoe upper holding finger 22. The sliding block 18 is mounted relatively to the wheel 10 so that the upper holding finger 40 22 has its end portion located laterally adjacent to the inclined rubbing surface of the wheel. The outer end of the finger 22 is shaped so as to present an upper supporting surface 24 substantially parallel to the inclined surface 14. The sliding block 18 is provided with a vertical hole to receive a compression spring 26 the upper end of which engages a ledge 28 attached to the machine frame.

50 Normally the spring maintains the finger pressed downwardly away from the inclined surface 14, and the bottom of the finger carrying block 18, or, strictly, the bottom of the ear 20 formed on the block, is shaped to 55 engage the bottom of the shoe. The frame of the machine is provided with an edge gage 30 received in guideways in the machine frame and projecting from the frame horizontally toward the lower portion of the 60 wheel and the finger. The purpose of this edge gage is to position the shoe within the field of operation of the lasting instrumentalities.

In the use of the machine, a shoe is supported 65 in the hand of the workman and suc-

cessive portions subjected to the action of the lasting instrumentalities. The shoe is first presented to the wheel with the bottom of the shoe uppermost and the margin of the upper disposed between the inclined rubbing 70 surface and the upper supporting finger 22. The wheel is being continuously rotated and the operator presses the shoe against the bottom of the finger carrying support 18 so as to move it upwardly against the action of 75 the spring 26, the finger thereby forcing the margin of the upper into position for it to receive the rubbing action of the surface 14 of the wheel, the amount of force which the operator uses in forcing the shoe against 80 the finger carrying support determining the degree of force applied by the rubbing surface.

Owing to the relative arrangement of the rubbing surface and the finger, the margin 85 of the shoe upper is disposed toward lasted position over the shoe bottom but somewhat removed so that there is no tendency of the margin of the shoe upper to adhere to the innersole, and, since the wheel is being ro- 90 rotated relatively to the stationary finger, a frictional drag is exerted upon the margin of the shoe upper. The effectiveness of this frictional drag is increased by the ribs and grooves formed on the rubbing surface 14 95 and tends to work the upper inwardly over the shoe bottom and thereby tension it about the last. Thus all excess fullness of the upper is worked over on to the shoe bottom and the upper tensioned into conformity 100 with the conformation of the last. By reason of the rubbing surface being inclined to the axis of rotation of the wheel, the frictional drag applied to the upper is directed in a plane oblique, transversely and longitudinally, to the plane of the shoe bottom. This arrangement is especially advantageous in that it exerts a progressively increasing tension to the margin of the upper from its outer edge inwardly. Moreover, it acts, in 110 effect, to plait the shoe upper so that it may be disposed to the best advantage upon the shoe bottom. Inasmuch as the upper is pulled about the last and into lasted position over the shoe bottom with a force de- 115 pending upon the frictional drag induced between the rubbing surface 14 and the relatively stationary finger under the manipulation of the shoe by the operator, a uniform application of tension may be applied to various portions of the shoe in accordance with the specific conditions; that is, the frictional drag may be more drastic about the toe and heel ends of the shoe, for example, than along the sides of the shoe.

Another advantage obtained by the described construction is that the portion of the shoe upper which is to be treated by the rubbing surface is held removed from the surface of the work, thus eliminating the 120 130

difficulties heretofore experienced in lasting shoes of this type by reason of the margin of the shoe upper becoming adhered to the innersole before it has been properly worked over into lasted position.

As the shoe is fed along, the positioned and tensioned margin of the shoe upper is disposed within the field of action of the laying surface 12 of the wheel for further treatment thereby. This surface acts to lay the margin of the tensioned upper into lasted position on the shoe bottom, or, in the type of shoe above mentioned, work the margin of the upper into adhesion with the innersole. By reason of the surface 12 being laterally adjacent to the upper positioning and tensioning means, the margin of the upper is acted upon by said surface before the tension of the upper is relaxed, and it will be seen that this result is further secured owing to the oblique plane in which the margin of the upper is treated by the rubbing surface. The surface 12 acts to work the upper in a direction inwardly and downwardly against the innersole with sufficient force to cause it strongly to adhere to the innersole.

It is to be noted that in the use of the machine as above described the entire margin of the shoe upper is subjected to the treatment of the machine, and, consequently, the surface 12 not only acts upon the portions of the upper which lie flat upon the shoe bottom, but also such portions of the upper which are necessarily pleated in order properly to conform the shoe upper to the last. This is of considerable importance inasmuch as it eliminates the necessity of a subsequent hand rolling operation to insure proper adhesion between the margin of the upper and the innersole to prevent later defective vulcanization and "reject" shoes. By proper manipulation of the shoe it may be found desirable in some instances to operate at opposite sides of the shoe alternately in order properly to draw the upper about the last and dispose the margin in proper position on the shoe bottom. Also, the action of the surface 12 of the wheel may be used to act upon portions of overlasted upper which were not adequately treated in the usual course. Since the laying surface 12 is substantially parallel to the edge of the shoe and to the plane of the shoe bottom, the margin of the shoe upper is worked over into lasted position without any tendency for the shoe upper to be distorted, and proper manipulation of the shoe may be taken advantage of to present the shoe to the machine for the lasting operation to be performed to the best advantage. In the machine illustrated, the results just described are due to the fact that the portion 14 of the wheel exerts a frictional drag upon the margin of the shoe upper and the portion

12 of the heel effects an immediate laying operation, both of the portions 14 and 12 being continuously operated.

Having fully described the invention, what is claimed as new and desired to be secured by United States Letters Patent is:—

1. A machine of the class described having, in combination, means constructed and arranged to exert a frictional drag upon the margin of a shoe upper to tension the upper about the last, and means for continuously laying the margin of the tensioned upper into lasted position on the shoe bottom before the tension of the upper is relaxed. 75

2. A machine for working the marginal portion of a shoe upper into lasted position having, in combination, means positioned to extend between the shoe bottom and the inturned margin of the upper and continuously movable means located adjacent to 85 said first-named means to lay said margin of the upper upon the shoe bottom.

3. A machine for working the marginal portion of a shoe upper into lasted position having, in combination, a finger positioned 90 to extend between the shoe bottom and the inturned margin of the upper, means for frictionally drawing said margin on to the finger and means located adjacent to the tip of the finger to lay said margin of the 95 upper upon the shoe bottom.

4. A machine for working the marginal portion of a shoe upper into lasted position having, in combination, a finger positioned 100 to extend between the shoe bottom and the inturned margin of the upper, means for frictionally drawing said margin on to the finger, the co-acting faces of the finger and said means being inclined relatively to the plane of the shoe bottom, and means located 105 adjacent to the tip of the finger to lay said margin of the upper upon the shoe bottom.

5. A machine for working the marginal portion of a shoe upper into lasted position having, in combination, a yieldingly mounted finger positioned to extend between the shoe bottom and the inturned margin of the upper, and continuously movable means located adjacent to the tip of the finger to 110 lay said margin of the upper upon the shoe 115 bottom.

6. A machine of the class described having, in combination, means to which the shoe may be presented initially to form the margin of the upper toward lasted position over the shoe bottom, and continuously movable means located adjacent to 120 said means constructed and arranged to lay the positioned margin into lasted position upon the shoe bottom. 125

7. A machine of the class described having, in combination, continuously operated means adapted to engage the margin of a shoe upper and work it inwardly over the shoe bottom, and a coöperating member ar- 130

ranged to hold the upper margin in engagement with the said working means.

8. A machine of the class described having, in combination, means adapted to engage the margin of a shoe upper, a coöperating member arranged to hold the upper margin in engagement with the said rotating means, and means located adjacent to the said rotating means and the said member constructed and arranged to force the margin into lasted position on the shoe bottom.

9. A machine of the class described having, in combination, two relatively movable members adapted initially to position a portion of the margin of a shoe upper toward lasted position over the shoe bottom, and means constituting a part of one of the said relatively movable members and constructed and arranged to lay an adjacent portion of the margin of the upper into lasted position on the shoe bottom.

10. A machine of the class described having, in combination, a rotating member having a surface adapted to operate upon the margin of a shoe upper, means for maintaining the upper margin in engagement with the said surface whereby the shoe upper is tensioned about the last, and a surface formed on said rotating member adjacent to the first-mentioned surface for laying the margin into lasted position upon the shoe bottom.

11. A machine of the class described having, in combination, a member having a continuous rubbing surface adapted to act upon the margin of a shoe upper, means for rotating the said member, a relatively stationary coöperating member constructed and arranged to cause the said rubbing surface of the rotating member to produce a frictional drag upon the margin of the shoe upper to draw the upper about the last.

12. A machine of the class described having, in combination, a member having a continuous rubbing surface adapted to act upon the margin of a shoe upper, means for rotating the said member, a relatively stationary coöperating member for maintaining the margin of the upper in position to

receive the action of the rubbing surface, and a continuous laying surface formed on the said rotating member constructed and arranged to lay the margin of the upper into lasted position on the shoe bottom.

13. A machine of the class described having, in combination, a rotating member having a continuous rubbing surface disposed in a plane inclined to its axis of rotation, and a relatively stationary member constructed and arranged to cause the said rubbing surface of the rotating member to produce a frictional drag directed angularly across the margin of the shoe upper to draw the upper about the last.

14. A machine of the class described having, in combination, a rotating member having a continuous rubbing surface disposed in a plane inclined to its axis of rotation, and a complementary laying surface extending substantially parallel to its axis of rotation, and a coöperating member located adjacent to the said inclined surface of the rotating member.

15. A machine of the class described having, in combination, a rotating member having a continuous rubbing surface disposed in a plane inclined to its axis of rotation, and a substantially horizontal complementary laying surface, and means arranged to cause the margin of the upper to be acted upon by the inclined surface to draw the margin toward lasted position over the shoe bottom and by the horizontal surface to lay the margin into lasted position on the shoe bottom.

16. A machine of the class described comprising, in combination, a rotating member having a continuous rubbing surface adapted to act upon the margin of a shoe upper, a relatively stationary coöperating member for maintaining the margin of the upper in position to receive the action of the rubbing surface, and means operating to lay the margin of the upper into lasted position on the shoe bottom.

In testimony whereof I have signed my name to this specification.

E. MARK SULLIVAN,
Administrator of Ronald F. McFeely, deceased.
